(57) **CLAIM**

The ornamental design for a functional pet feeder insert, as shown and described.

DESCRIPTION

FIG. 1 is a top perspective view of a functional pet feeder insert according to the preferred embodiment of the present invention;

FIG. 2 is a front perspective view thereof;

FIG. 3 is a top plan view thereof;

FIG. 4 is a front elevational view thereof;

FIG. 5 is a top perspective view of a functional pet feeder insert according to a second embodiment, adapted for conditioning a pet for scent and nose work training; and,

FIG. 6 is a top perspective view of the functional pet feeder insert of FIG. 5, shown in use with a pet bowl.

The broken line showing of a pet bowl in FIG. 6 is for illustrative purposes only and forms no part of the claimed design.

1 Claim, 6 Drawing Sheets(56)
